Primary Examiner — Kelley Donnelly*(74) Attorney, Agent, or Firm* — Holtz, Holtz, Goodman & Chick, P.C.(57) **CLAIM**

The ornamental design for a shelf with lip, as shown and described.

DESCRIPTION

FIG. 1 is a top, front, left side perspective view of a first embodiment of a shelf with lip showing my new design; FIG. 2 is a bottom, rear, right side perspective view thereof; FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top, front, left side perspective view of a second embodiment of a shelf with lip showing my new design, the front, right and left side elevational views being the same as shown in FIGS. 5, 7 and 8, respectively;

FIG. 10 is a bottom, rear, right side perspective view thereof; FIG. 11 is a top, front, left side perspective view of the first embodiment of the shelf with lip showing indeterminate width of the shelf with lip; and,

FIG. 12 is a bottom, rear, right side perspective view thereof.
